UNITED STATES PATENT OFFICE.

FRANK G. FEELEY, OF CHICAGO, ILLINOIS, ASSIGNOR TO M. D. KNOWLTON COMPANY, OF ROCHESTER, NEW YORK, A CORPORATION OF NEW YORK.

MACHINE FOR MAKING CORRUGATED PAPER-BOARD.

1,264,041.

Specification of Letters Patent. Patented Apr. 23, 1918.

Application filed December 7, 1915. Serial No. 65,471.

To all whom it may concern:

Be it known that I, FRANK G. FEELEY, a citizen of the United States, and resident of Chicago, in the county of Cook and State of Illinois, have invented certain new and useful Improvements in Machines for Making Corrugated Paper-Board, of which the following is a specification.

This invention relates to machines for manufacturing corrugated paper and like material, and more particularly to machines for lining the corrugated paper. In such a machine it has been proposed, as disclosed in the pending application of Edgar M. Hawkins, Serial No. 69,093 filed December 28, 1915, to transfer the paper corrugated by a pair of corrugating rolls to a corrugated or toothed rotary drum on which the corrugated paper is held while adhesive is applied to the same and while a liner is applied to the adhesive-coated corrugated paper.

It is the object of the present invention to so construct or form the teeth on the drum that the adhesive-applying mechanism will not apply adhesive to the drum teeth when no corrugated paper is present thereon, or when holes or openings occur in the corrugated paper.

As disclosed but not claimed in the pending application above referred to, this is accomplished by providing the drum with so-called "stub-teeth", or, in other words, teeth which are of less height than the corrugations of the corrugated paper. The adhesive-applying mechanism is so positioned as to supply the ridges of the corrugations of the corrugated paper with adhesive and the extremities of the drum teeth are, therefore, spaced from the surface of the adhesive-applying member. This spacing is sufficient to prevent adhesive from being applied to the drum teeth when tears or other openings occur in the corrugated paper, or when no corrugated paper is present, on the drum.

The invention is illustrated in the accompanying drawing, in which:—

Figure 1 is a vertical section through a corrugating and lining machine, showing the disposition of the drum, corrugating rolls and adhesive-applying mechanism;

Fig. 2 is a sectional detail view showing a portion of the drum and adjacent corrugating roll and illustrating the relation be-

tween the teeth of the corrugating rolls and the drum, and the manner in which the corrugated paper is transferred from the corrugating rolls to the drum; and

Fig. 3 is a vertical section on an enlarged scale showing a portion of the drum, the corrugating rolls and the adhesive-applying mechanism and illustrating the relation between the teeth of the drum and the adhesive-applying roll of the adhesive-applying mechanism.

Fig. 1 shows only so much of the complete corrugating and lining machine disclosed in the above-mentioned application as will give a correct understanding of the present invention. Referring particularly to Fig. 1, it will be seen that the drum hereinbefore referred to is indicated at A, and that the corrugating rolls are denoted generally by the reference character B. The purpose of the rolls B is to corrugate a web of paper or other material a and to transfer it to the surface of the drum A. While the corrugated web is being carried by the drum A, the adhesive-applying mechanism, designated generally by C, applies adhesive to the ridges of the corrugations on the corrugated paper, thereby placing the same in condition to receive a liner b conducted to the surface of the drum by means of the guide rollers D. The web b is first passed over a preheating device E, but as the construction of this preheating device forms no part of the present invention, the same will not be herein described.

The drum A carries the lined corrugated paper through substantially 270° to a transfer roll F, which serves to remove the lined corrugated paper from the surface of the drum and direct the same over a heating bed, shown in part at G. Various other parts enter into the construction of the complete machine, but the present invention relates particularly to the construction of the teeth on the drum A and the relation between such teeth and the teeth on the corrugating rolls or the corrugations on the paper formed by such teeth.

Figs. 2 and 3 show this relation, from which it will be noted that the teeth 1 on the corrugating rolls B are full size teeth and form corrugations in the web a of predetermined height, but that the teeth 2 on the surface of the drum A are reduced in length and constitute so-called stub-teeth.

When the corrugated web *a* is transferred to the surface of the drum *A* from the adjacent corrugating roll, the ridges of the corrugations of the corrugated web are spaced from the tops of the teeth on the drum, as clearly indicated at 5 in Fig. 2. This is due to the fact that the corrugations on the corrugated paper are of greater height than the teeth of the drum, because the teeth on the corrugating rolls are of greater height than the teeth on the drum.

After the web *a* is corrugated between the corrugating rolls, it is stripped from the outer roll 21 by means of suitable stripper fingers, such as 3', extending into circumferential grooves or channels in said roll, and is then engaged by the guide 4' and held thereby in the corrugations of the inner roller 22 until carried by the latter to a point between it and the drum *A*. Thereafter, the filler, in its continued feeding movement, is transferred from said inner roll 22 to the surface of the drum by the stripper fingers 3 and guide 4, the said fingers extending into circumferential grooves or channels in said roll as shown.

The adhesive-applying mechanism *C* comprises an adhesive pan 6, a distributing roll 7, and an adhesive-applying roll 8. The adhesive-applying roll 8 is journaled in a casting 9, which is mounted to slide upon a bracket 10 secured to a suitable part of the frame of the machine. The roll 7 is mounted in sliding bearings 11 which are mounted to slide on the casting 9. By this means, both rolls 7 and 8 may be unitarily adjusted toward and away from the drum *A* by sliding the casting 9 on the bracket 10. This is accomplished by means of a link 12 pivoted to a rock arm 13, which is mounted to oscillate about the axis of a shaft 14. A hand lever 15 serves to shift the rock arm 13, and hence move the rolls 7 and 8 into and out of their operative position. The inward movement of the rolls 7 and 8, and hence the relation between the roll 8 and the ridges of the corrugations on the web is determined by the length of the link 12 and the arm 13. The length of these parts may be varied by the insertion or removal of one or more washers 16 capable of being inserted between a swivel block 17 pivoted to the rock arm 13 and an adjacent shoulder on the link 12, as shown. The inward movement of the adhesive-applying roll 8 is, therefore, positively limited and the distance between the adhesive-applying roll and the extremity of the drum teeth may be adjusted.

The distributing roll 7 may be adjusted with respect to the adhesive-applying roll 8 by means of the thumb-wheels 19, which, when turned, slide the bearings 11 on the casting 9 to vary the space between the rolls 7 and 8. The adjustment of the roll 7, as well as the feature of dropping the adhesive

pan 6 away from the rolls by manipulating a hand lever 20, have no bearing upon the present invention and will not be described in greater detail.

It will be noted that the adhesive-applying roll 8 is so adjusted that its surface comes in contact with the ridges of the corrugations on the corrugated web, and, therefore, applies adhesive to the ridges of such corrugations. The tops of the drum teeth, however, being of less height than the corrugations of the web are spaced from the surface of the roll 8 and will not receive any of the adhesive either when the corrugated web does not intervene between the roll 8 and the drum, or when tears or openings occur in the web. If the teeth on the drum were made of the same height as the corrugations on the web, such tears or openings in the web would permit adhesive to be applied through such openings on to the surface of the drum, which, of course, is objectionable.

The liner *b* is brought into contact with the adhesive-coated corrugated paper by means of the rolls *D*. The liner, in passing around the drum *A* with the corrugated paper, is pressed against the same and adheres thereto and the lined corrugated paper then passes over the transfer roll *F* to the heating pan *G* where the adhesive is dried.

It will, therefore be noted from the above description that the novel formation of the teeth on the drying drum and the relation between such teeth, the teeth of the corrugating rolls, and the height of the corrugations of the web, renders it possible to apply adhesive to the ridges of the corrugations on the web without danger of the drum receiving any of the adhesive when a portion of the web does not intervene between the surface of the drum and the surface of the adhesive-applying roll. The shortening of the teeth on the drum does not interfere with the proper accommodation of the web corrugations in the recesses between the teeth of the drum, and the function of the teeth of the drum, *i. e.*, maintaining the web corrugations in spaced relation until secured by the liner adhesively applied thereto, is performed just as efficiently by the stub teeth as if the teeth of the drum were of sufficient size to entirely fill the corrugations of the web.

It is obvious that the present invention is applicable to all machines having corrugating means and a receiving member for receiving the corrugated material, irrespective of whether the corrugating means comprises rolls or whether the receiving member is a drum, as in the present instance. The teeth 2 might be formed on any kind of receiving member and the corrugating might be done on toothed members other than the rolls *B* herein disclosed.

What I claim is:—

1. In a corrugating machine, the combination of corrugating rolls, a toothed drum to receive the material corrugated by said rolls, and means for applying adhesive to the ridges of the corrugations of said material while the latter is being carried by said drum, the teeth on said drum being of less height than the corrugations of the material 70 corrugated by said rolls. 75
2. In a corrugating machine, the combination of toothed corrugating rolls, a toothed drum to receive the material corrugated by said rolls, and means for applying adhesive to the ridges of the corrugations of said material while the latter is being carried by said drum, the teeth on said drum being of less height than the teeth of the corrugating rolls, for the purpose described. 80
3. In a corrugating machine, the combination of toothed corrugating means, a toothed receiving member for receiving the material corrugated by said means, and means for applying adhesive to the ridges of 85 the corrugations of said material while the latter is being carried by said member, the teeth on said member being of less height than the teeth on said corrugating means, for the purpose described. 90
4. In a corrugating machine, the combination of toothed corrugating means, a toothed receiving member for receiving the material corrugated by said means, and means for applying adhesive to the ridges of 95 the corrugations of said material while the latter is being carried by said member, the teeth on said member being of less height than the corrugations on the material corrugated by said means. 100
5. In a corrugating machine, the combination of corrugating means, a toothed receiving member for receiving the material corrugated by said means, and adhesive-applying means for applying adhesive to 105 the ridges of the corrugations of the corrugated material while the latter is being carried by said member, the teeth of said member being of less height than the corrugations of said material so that no adhesive will be applied to such teeth by the adhesive-applying mechanism. 110
6. In a corrugating machine, the combination of corrugating means, a toothed receiving member for receiving the material corrugated by said means, adhesive-applying mechanism comprising an adhesive-applying roll for supplying the ridges of the corrugated material with adhesive while said material is carried by said member, and 115 means to adjust said adhesive-applying roll toward and away from the drum, the teeth on said member being of less height than the corrugations on the corrugated material, for the purpose described. 120
7. In a corrugating machine, the combination of corrugating rolls and a toothed drum to receive the material corrugated by said rolls, the teeth on said drum being of less height than the corrugations on the material corrugated by said rolls, and adhesive-applying mechanism comprising an adhesive-applying roll positioned to apply adhesive to the ridges of the corrugations of said material while the material is being carried by said drum. 125
8. In a corrugating machine, the combination of corrugating rolls and a toothed drum to receive the material corrugated by said rolls, the teeth on said drum being of less height than the corrugations on the material corrugated by said rolls, and adhesive-applying mechanism comprising an adhesive-applying roll positioned to apply adhesive to the ridges of the corrugations of said material while the material is being carried by said drum. 130
9. In a machine of the character described, the combination of toothed corrugating rolls, a corrugated carrying roll having ribs of less depth than the teeth of said corrugating rolls, and means for applying paste to crowns of material corrugated by said corrugating rolls and passing over 95 said carrying roll. 100
10. In a machine of the character described, the combination of means for corrugating sheeted material, a carrying roll having corrugations adapted for holding the corrugations of said material substantially to pitch, the corrugations of said roll being less in depth than the corrugations of said material, and means for applying an adhesive and backing to the crowns of the corrugations of said material while engaged by said roll. 105
11. In a machine of the character described, means for forming corrugations in sheeted material, mechanism for applying adhesive to crowns of corrugations formed in material by said means, and means for supporting the bases of said corrugations while leaving the crowns thereof free during the application of adhesive thereto. 110
12. A corrugated paper making machine comprising a pair of opposed rolls having corrugated peripheries between which a paper sheet is adapted to be impressed, a third roll provided with a periphery fashioned with corrugations of lesser projection than the corrugated paper sheet issuing from between said first mentioned rolls, a glue dabbing device mounted for movement with a predetermined limit toward said third roll 120 and means for moving said device toward or away from such limit. 125
13. A corrugated paper making machine comprising a pair of opposed rolls having corrugated peripheries between which a 130

paper sheet is adapted to be impressed, a third roll provided with a periphery fashioned with corrugations of lesser projection than the corrugated paper sheet adapted to be conveyed upon the same, a glue dabbing device mounted for limited movement toward said roll, the arrangement being such as to permit of dabbing contact only with the elevated portions of the passing sheet, and means for controlling the supply of glue upon said device.

14. A corrugated paper making machine comprising a pair of opposed rolls having corrugated peripheries between which a paper sheet is adapted to be impressed, a third roll having its periphery fashioned with shorter corrugations and positioned beyond with reference to the course of travel of such sheet, a glue dabber arranged along said third roll and out of contact with such shorter corrugations thereof, for the purpose specified.

15. A corrugated paper making machine comprising a pair of opposed corrugated impressing rolls between which a paper sheet is adapted to pass, a third roll located beyond the point of delivery from, and having corrugations fitted to but of lesser height than those of, the first mentioned rolls, and a

glue dabber adjacent said third roll and projecting between the tangential planes of the passing outermost portions of said sheet and third roll corrugations respectively whereby to contact the former but not the latter.

35
16. In a machine of the character described, meshing corrugating rollers having channels therein, a carrying roller meshing with one of said corrugating rollers, said carrying roller having ribs of less depth than those of the roller with which it meshes, means extending into channels of said corrugating rollers for stripping material therefrom and guiding said material to a succeeding roller, a roller for applying an adhesive to crowns of said material as it passes over said carrying roller, and a roller for applying a backing to said crowns as the material passes over said carrying roller from said roller for applying adhesive.

50
Signed at Chicago, in the county of Cook, and State of Illinois, this 4th day of December, A. D. 1915.
